US00D897929S

(12) **United States Design Patent** (10) Patent No.: **US D897,929 S**
(45) Date of Patent: **** Oct. 6, 2020**

(54) **CONTROLLER FOR ROTORCRAFT**

(71) Applicant: **ESSEX INDUSTRIES, INC.**, St. Louis, MO (US)

(72) Inventors: **Charles Culp**, Webster Groves, MO (US); **Greg Kemner**, Cottleville, MO (US); **Bob Hale**, Cincinnati, OH (US)

(73) Assignee: **ESSEX INDUSTRIES, INC.**, St. Louis, MO (US)

(**) Term: **15 Years**

(21) Appl. No.: **29/674,985**

(22) Filed: **Dec. 27, 2018**

(57) **CLAIM**

The ornamental design for a controller for a rotorcraft, as shown and described.

DESCRIPTION

FIG. 1 is a left rear perspective view of a controller for a rotorcraft showing our new design.

FIG. 2 is a front view of the controller for a rotorcraft.

FIG. 3 is a rear view of the controller for a rotorcraft.

FIG. 4 is a left sided view of the controller for a rotorcraft.

FIG. 5 is a right side view of the controller for a rotorcraft.

FIG. 6 is top plan view of the controller for a rotorcraft; and,

FIG. 7 is a bottom plan view of a controller for a rotorcraft.

The broken lines shown in the drawings depict portions of the controller for a rotorcraft that form no part of the claimed design.

1 Claim, 7 Drawing Sheets
